GAME PADDLE

Marc Bomse, New York, N. Y.

Application January 29, 1953, Serial No. 23,345

Term of patent 14 years

(Cl. D34—5)

To all whom it may concern:

Be it known, that I, Marc Bomse, a citizen of the United States of America, residing at New York city, in the county and State of New York, have invented a new, original, and ornamental Design for a Game Paddle, of which the following is a specification, reference being had to the accompanying drawing, forming a part hereof.

In the drawing:

Figure 1 is a front elevational view of a game paddle, showing my new design;

Figure 2 is a side view of the game paddle, shown in Figure 1. Both sides and faces of the paddle are identical in appearance.

Portions of the drawing figures are stippled to indicate color and texture contrast.

I claim:

The ornamental design for a game paddle, substantially as shown and described.
